UNITED STATES PATENT OFFICE.

MAX WENZEL, OF MULDENSTEIN, KREIS BITTERFELD, GERMANY.

SUCTION BOX FOR PAPER MACHINES AND THE LIKE.

Application filed January 9, 1924. Serial No. 685,247.

To all whom it may concern:

Be it known that I, MAX WENZEL, a citizen of the State of Saxony, residing at Rittergut Muldenstein, No. 1 in Muldenstein, Kreis Bitterfeld, Germany, have invented certain new and useful Improvements in Suction Boxes for Paper Machines and the like, of which the following is a specification, reference being had to the accompanying drawings.

My invention relates to a suction-box, in which in the upper longitudinal portion thereof are mounted rolls, arranged for carrying the wire of the paper-making machine out of frictional contact with any part of the box; and the object of the rolls thus arranged is to lessen the wear on the wire in its passage over the suction-box, and consequently to lengthen the life of said wire.

In a device of this kind it is a problem to find a suitable device for excluding the passage of air between the box and the rolls carrying the wire. The object of the present invention is to provide a joint between the immovable parts of the suction-box and said rolls, of sufficient width that water adhering on said rolls or dammed up by the ends of said rolls is drawn in the joint for the purpose of sealing and rinsing the joint, thus preventing the passage of air and the stopping thereof with pulp.

The invention consists in the features of construction and combinations of parts hereinafter described and specified in the claims.

In the accompanying drawings, illustrating the preferred embodiment of my invention:

Figure 1 shows certain parts in a side elevation and other parts in a vertical cross-sectional view of the suction-box; Fig. 2 shows a central vertical longitudinal sectional view thereof, partly in section on line *a a* and on line *b b*; and Figs. 3, 4 and 5 are vertical cross-sectional views on an enlarged scale of detached details.

Similar numerals indicate like parts in the several views.

Referring more particularly to the drawings and more particularly to Figures 1 and 2, wherein I have shown my improved suction-box, there is in this instance, the combination of three units. On each side of

the paper-making machine, frames 1 are arranged for supporting the suction-box, the said frames being either a part of the frame of the paper-making machine or only a part of the suction-box. Between said frames 1, sheets 2 are arranged which are screwed on each end to the frames, the said sheets separating the single units of suction boxes from the suction rooms and the atmosphere.

The end pieces 3, being secured on the frames 1, are preferably composed of a lower part and an upper part, which are divided in the central plane of the wire-carrying rolls 4, thus to facilitate the putting in of said rolls. The end pieces serve to close the space between and around the ends of the wire carrying rolls 4, the frame 1 and the wire 5. The closure is created by means of a joint, left between the surfaces of the wire-carrying rolls and the adjacent parts of the end pieces, and water, which is dammed up before the ends of the rolls, for example, by means of a vertical wall of the end piece, is drawn into the joint, in order to seal and to rinse the joint, thus preventing the passage of air and the stopping with pulp. The surface of the end pieces opposite to the surface of the wire-supporting rolls, are preferably fitted with a nonrusting material, as, for example, rubber, wood, metal. Supporting bearings 6 are preferably secured to the flanges of the end pieces 3 or to the frames 1. The wire-carrying rolls 4 are mounted in said supporting bearings for revolution with the traveling machine-wire.

Fitted in between the wire-carrying rolls 4 and the machine-wire 5, near each end of the box mounted on and guided in the end pieces 3, are movable deckle heads 7 for adjusting the length of the suction part of the box to the width of the web of paper 8, which is being made. The upper surface of these deckle heads is curved to conform to the adjacent bend of travelling wire, which sags between the wire-carrying rolls due to the atmosphere pressure against the wire. The purpose of the heads 7 is to provide an easy bearing surface for the wire blanket or, more preferably, to create a joint between the curved upper surface of the deckle heads and the travelling wire. The deckle heads are operated by means of adjusting screws 9. Water is preferably

supplied to the joint between the end pieces and the rolls by means of the hollow shaft of the deckle heads 7, which water will escape through the ports 10 and may serve for rinsing the joint and the opposite surface of the rolls. The deckle head should be made preferably of a suitable nonrusting material.

The tightening ledges 11 extend along the rolls from one end piece to the other and border tightly on the said end pieces 3, secured to the longitudinal sheets 2, forming the joint for tightening the suction room against the atmosphere and also separate the single units of the suction-box. The tightening ledges may be formed in a variety of ways so as to adapt the same to varying conditions. If the difference of degree of vacuum between two units of suction-box or between the suction-rooms and atmosphere is very great, the tightening ledge is preferably curved to conform to the surface of the adjacent wire-supporting rolls for the purpose of creating a broad joint to prevent the passage of air. This modification is shown by Figure 4. If the difference of degree of vacuum before and behind the joint is not relatively great, the tightening ledge may also be straight and even-surfaced against the rolls, shown by Figures 3 and 5. I also prefer this modification so as to prevent contact between the carrying rolls and the opposite surface of the tightening ledge, though the said rolls may sag somewhat in the event the rolls are made for wide machines.

The surface of the tightening ledge, which is turned to the roll is preferably fitted with any suitable non-rusting material (rubber, metal, wood and the like) or is composed of a strip of this material, shown by Figure 5. If the joint is not wide enough, water cannot rinse through the joint, and pulp will stop it causing such friction as to disastrously retard or stop the rolls. But also, if the joint is too wide, air is drawn into the suction rooms and a large vacuum creating apparatus is necessary so that the air does not interfere with the suction and its successful operation upon the paper in the wire.

The bottom pieces 12 are arranged under and between the frames 1 and the sheets 2 and may be secured to the frames and sheets by any convenient means, as, for example, by screws. The pipes 13 and 14 for removing water and air are preferably separated and may be connected with said bottom piece. The air exhaust pipe 14 is arranged partly inside and partly outside of said bottom piece, having its upper inside end 15 open and terminating above the level of the extracted water, and being connected to a suitable vacuum creating apparatus at its outer end 16. Above the aforesaid open end a plate 17 may be arranged, so that the ex-

tracted water cannot drop into the exhaust pipe. Preferably the plate dips into the water with its longitudinal edges, which are curved down that it will form a channel way to conduct the air out of contact with the dropping water. The pipe 13 for conducting the extracted water is arranged under and outside of the bottom piece and may be formed to act in that case like a siphon 18. The outside plate 19, which forms the air exhaust pipe in connection with the bottom piece, may be strengthened against the atmospheric pressure by the stiffeners 20.

If a very high degree of vacuum is employed in the last units of suction-box, it will cause such an atmospheric pressure against the wire, that the travelling wire sags deeply between the wire-supporting rolls and it is desirable in this instance to arrange supporting laths 21. In order that the pressure, and consequently the friction of the wire in passing over the supporting laths may be reduced to a minimum, the upper edges of said supporting laths are arranged preferably under the level of the top of the rolls. The supporting laths are carried by one or more supports 22, which are mounted on the sheets 2 or on arms 23 secured on the sheets 2. The said laths may be made of such a material as is best adapted to save the wire mesh blanket; for example it may be wood, leather, rubber or some relatively soft material.

If a very high degree of vacuum is required in the last units of suction-box another modification may be arranged behind the last roll, which includes a suction-box 24 of common construction connected to, as shown, or separated from the unit and fitted with wooden covers corresponding to the present practice. In this case the supporting laths first mentioned are not necessary.

Any desired number of suction-boxes or units of suction-boxes can be arranged upon one paper-making machine or any desired number of rolls in one box for effectually removing the water on the web of paper.

The suction-box may be arranged with wheels or carried by any suitable apparatus to facilitate removing when changing wire.

What I claim is:

1. A suction-box comprising supporting frames, sheets transversely arranged between said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls near each end thereof for adapting the working length of said box to the width of paper being made, tightening ledges resting on said sheets, and extending along said rolls

- from one side to the other, bordered tightly on said end pieces and leaving a joint against the adjacent surface of the wire-supporting rolls, all of said joints being 5 wide enough to be sealed and rinsed by water but near enough to make difficult the passage of air.
2. A suction-box comprising supporting frames, sheets transversely arranged between 10 said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls near each end thereof for adapting the working length of said box to 15 the width of paper being made, tightening ledges resting on said sheets, extending along said rolls from one side to the other, bordered tightly on said end pieces and leaving a joint against the adjacent surface of 20 wire-supporting rolls, said end pieces having vertical walls whereby the water, for sealing and rinsing the joints between said end pieces and said rolls is dammed up before the ends of said rolls.
3. A suction-box comprising supporting frames, sheets transversely arranged between 25 said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls 30 near each end thereof for adapting the working length of said box to the width of paper being made, tightening ledges resting on said sheets, extending along said rolls from one side to the other, bordered tightly on said end pieces and leaving a joint against the adjacent surface of wire-supporting rolls, a plate being 35 arranged above the inside open end of an air exhaust pipe and dipping into the water with its longitudinal edges, said edges being curved downwardly to form a channel way to conduct the air out of contact with dropping water.
4. A suction-box comprising supporting frames, sheets transversely arranged between 40 said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls near each end thereof for adapting the working length of said box to the width of paper being made, tightening ledges resting on said sheets, extending along said rolls from one side to the other, bordered tightly on said end pieces and leaving a joint against the adjacent surface of wire-supporting rolls, the surfaces of said tightening ledges and said end pieces adjoining the wire-supporting rolls being of a non-rusting material.
5. A suction-box comprising supporting frames, sheets transversely arranged between 45 said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls near each end thereof for adapting the working length of said box to the width of paper being made, tightening ledges resting on said sheets, extending along said rolls from one side to the other, bordered tightly on said end pieces and leaving a joint against the adjacent surface of wire-supporting rolls, and wire-bearing laths arranged under the wire between and lengthwise of said rolls to support the wire when a very high degree of vacuum is employed.
6. A suction-box comprising supporting frames, sheets transversely arranged between 50 said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls near each end thereof for adapting the working length of said box to the width of paper being made, tightening ledges resting on said sheets, extending along said rolls from one side to the other, bordered tightly on said end pieces and leaving a joint against the adjacent surface of wire-supporting rolls, and wire-bearing laths arranged under the wire between and lengthwise of said rolls to support the wire when a very high degree of vacuum is employed.
7. A suction-box comprising supporting frames, sheets transversely arranged between 55 said frames, bottom pieces arranged between said frames and sheets, wire-supporting rolls carried by said frames, end pieces mounted on said frames and closing the space between the ends of said rolls and said frames by leaving a joint against the adjacent sides of all of said rolls, deckle heads arranged to slide on said end pieces between said rolls near each end thereof for adapting the working length of said box to the width of paper being made, tightening ledges resting on said sheets, extending along said rolls from one side to the other, bordered tightly on said end pieces and leaving a joint against the adjacent surface of wire-supporting rolls, and wire-bearing laths arranged under the wire between and lengthwise of said rolls to support the wire when a very high degree of vacuum is employed.

adjacent sides of all of said rolls, deckle heads arranged to slide on said end pieces between said rolls near each end thereof for adapting the working length of said box to the width of paper being made, tightening ledges resting on said sheets, extending along said rolls from one side to the other, bordered tightly on said end pieces and leaving a joint against the adjacent surface of wire-supporting rolls, and a suction box arranged behind the last wire-supporting roll and connected tightly with the said sheets and the said end pieces. 10

MAX WENZEL.
